BODIES FOR COMPACTION TRUCKS AND
THE LIKE

Phil Cadotte, 30½ Meadow St., Norwalk, Conn.
Original application Mar. 15, 1963, Ser. No. 265,450.
Divided and this application Apr. 23, 1964, Ser. No. 377,149

5 Claims. (Cl. 296—101)

This is a division of application Serial No. 265,450, filed Mar. 15, 1963. This invention relates to a vehicle body and particularly to a body of the kind employed for collecting refuse, including cartons, cans and the like as well as garbage. In such bodies means have been provided for moving longitudinally of the body to compact the collected cartons, cans and other refuse from time to time, and also to discharge the contents of the body.

Compaction bodies have usually been employed to collect refuse from factories and other commercial establishments and are too long and too high to be practical for use in residential driveways and yards. And they have been too expensive for such.

It is an object of this invention to provide such a body which will be practical for residential use.

Another object of the invention is to provide such a body of improved structure, which will be durable and at the same time economical to build.

Another object is to provide such a body of reduced height which will nevertheless have a large capacity in proportion to its height and length.

Other features of the invention reside in many details of structure. The invention will best be understood if the following description is read in connection with the drawings in which

FIGURE 1 is a perspective view of the frame of the body,

FIGURE 2 is a side elevation of a complete body,

FIGURE 3 is a front elevation of the body shown in FIGURE 2,

FIGURE 4 is a top plan view, partly broken away and in section, looking down on the forward portion of the structure shown in FIGURE 2 including the compacting blade,

FIGURE 5 is a perspective view partly broken away and in section, showing the structure of the compacting blade and the means for supporting it and keeping it disposed at right angles to the side walls of the body.

FIGURE 6 is a vertical section taken on line 6—6 of FIGURE 2,

FIGURE 7 is a detail plan view showing means for demountably securing the body on a truck chassis,

FIGURE 8 is a vertical section taken on the line 8—8 of FIGURE 7,

FIGURE 9 is a detail transverse sectional view taken on the line 9—9 of FIGURE 2, showing how the support tract for the compaction blade is itself supported,

FIGURE 10 is a top plan view of the structural detail shown in FIGURE 9,

FIGURE 11 is a detail view partly in longitudinal vertical section taken on the line 11—11 of FIGURE 3 showing how one end of the cylinder and piston combination which moves the compaction blade is mounted at the front end of the track on which the blade is mounted, and

FIGURE 12 is a detail view partly in longitudinal vertical section taken on the line 12—12 of FIGURE 6 showing how one end of the cylinder and piston combination which opens and closes the body rear end or cover is mounted at the rear end of the track on which the blade is mounted.

In the embodiment of the invention shown and de-

2

scribed herein the body comprises a frame constructed of channel members supporting sides, floor and top of sheet metal. The way these parts are interrelated constitute features of the invention. It will be noted for example that the two level floor provides a body which may be wide in relation to its height. Or stated another way, it makes it possible to keep down the height of the body while compensating in width for the reduction in height.

It will also be noted that the top is formed of strips of sheet metal extending transversely of the body and interrelated and interconnected with one another and with vertical frame members and the sheet metal sides in ways which are features of the invention. Other features are the way the track beam, on which the compacting blade is mounted, is supported inside the body; the way the cylinder and piston combinations for moving the blade and for opening and closing the rear end cover respectively are mounted at opposite ends of the track; the way in which the whole body is secured on a truck chassis; and the structure of the blade and the way it is attached to its cylinder and piston combination making it possible to move the blade all the way to the front end of the body, thus making it possible to utilize the full length of the body, which in turn makes it practical to use bodies of reduced length.

Referring now to FIG. 1, it will be seen that the frame comprises a bottom having the outside longitudinal members 10 and 12 respectively comprising the portions 10a and 10c interconnected by the upwardly curved wheel cover portion 10b, and the portions 12a and 12c interconnected by the upwardly curving wheel cover portion 12b; the longitudinal members 14 and 16 disposed in parallel relation between the outside members 10 and 12, and spaced apart a distance which is the conventional distance between longitudinal members of a truck chassis, for mounting the body on a chassis as will be explained, and a number of cross members 18 extending between the outside members 10 and 12 and interlocked with the members 14 and 16.

Vertical members 20, 22 and 24 extend up from bottom member 10 and vertical members 26, 28 and 30 extend up from bottom member 12, in opposed relation to members 20, 22 and 24.

The members 20 and 26, 22 and 28, and 24 and 30 are interconnected at the top by members 32, 34 and 36 respectively.

The longitudinal members 37 are provided along the sides of the frame.

The floor is made with two levels. The main portion 38 rests on, and is welded to, the bottom members 14 and 16 and the portions of the cross members 18 which are spaced from the lateral margins of the bottom a distance equal to the depth of the wheel housings defined by the wheel cover portions 10b and 12b which in use extend over the rear wheels of the chassis. The lateral marginal portions 40 and 42 of the floor are offset above the main portion 38 a distance equal to the height of the wheel cover portions 10b and 12b and extend over the wheel covers respectively. A unitary pieces of sheet metal may be bent to form the floor, or it may preferably be made of three pieces with inner edges of the marginal strips bent down and then inwardly to provide an inner edge portion at the height of the center portion of the floor and adapted to overlap and be welded to the main center portion.

Transverse ribs 43 welded to the sides respectively extend under the marginal portions 40 and 42 of the floor to strengthen them.

The sides 44 and 46 are formed by attaching sheet metal to the inside surfaces of upright frame members 20, 22 and 24 and 26, 28 and 30 respectively, and the

longitudinal side frame members 37. As seen in FIGS. 3 and 6, the sheet metal sides are extended down below the level of the portions 40 and 42 of the floor and the outer edge margins of said portions are welded to the sides respectively.

The top of the body is formed of strips 48 of sheet metal extending transversely of the frame. The ends of strips 48 are bent down over, and welded to, the sheet metal sides. Where the ends of the strips encounter upright frame members 20, 22, 24, 26, 28 and 30, the upper edge portions of the frame members are cut away or offset as at 49 to receive the bent-over ends of the strips which are thus engaged between the sheet metal sides and the inner surfaces of the offset faces of the upper ends of the upright members of the frame.

The strips are interengaged along their abutting edges by means which provides increased strength. One edge of each strip is folded upward in an inverted U bend 50 and the other edge is bent up to form a single upwardly extending flange 52. The flange 52 of one strip is force fitted into the U-bend 50 of the abutting strip, thus forming a top of interlocked strips which is strengthened by the transverse ribs 54 comprised by the members 50 and 52.

As stated above, the bottom frame members 14 and 16 are spaced apart to register with and rest on the longitudinally extending members 56 and 58 respectively of a truck chassis. The body is secured on the chassis by the clamp means shown in FIGS. 7 and 8. The floor 38 of the body extends over the frame members 14 and 16. Pairs of bolts 60 and 62 are welded to opposite sides of spacing members 64 and 66 which are welded to opposite faces of members 14 and 16. The bolts of each pair extend down below the chassis members 56 and 58 respectively, and are interconnected by a cross member 68 which extends under the chassis support member and may be raised up against the under surface of the chassis support member by tightening the nuts 70, 72 on the bolts. By unscrewing the nuts 70, 72 and removing the cross members 68 from the pairs of bolts the body can be quickly disconnected from the supporting chassis.

In the body as illustrated in FIG. 2, the upper portion of the space between the upright frame members 20, 22 and 26, 28 is not covered with sheet metal, leaving openings W the lower edges of which may be defined by the members or sills 74 extending between members 20, 22 and 26, 28 respectively. The refuse is loaded into the body through the openings W. From time to time it may be pushed toward the rear of the body and compacted by a compacting blade indicated generally by the numeral 76, which is constructed as will be described. In FIG. 2 blade 76 is shown in full lines at the extreme front of the body in position to move toward the rear of the body, and to compact refuse loaded into the body through a space or window W. It is also shown in dotted lines in a position near the rear end of the body.

The blade 76 is mounted on a trolley 78 comprising rollers which rest on the oppositely extending lower flanges of an I beam 80 which thus defines a track. The I beam extends under the top of the body along its longitudinal mid-line and is supported by the top cross frame members 32, 34 and 36 to which it is welded through slots 82 provided in the portions of the top strips which are disposed between the cross frame members and the beam.

The I beam 80 is tapered upwardly adjacent its ends and one end of a telescopic cylinder and piston combination 84 of known kind is pivoted just beyond the front end of the beam on a cross pin 86 extending between downwardly extending portions of two parallel pieces of sheet metal which are extended rearwardly and bridged across the top, thus forming a hood 88 which is welded to the top of the I beam at its front end where it is not covered by a top strip 48, and is also slotted on its sides to engage and be supported by the short channel

member 90 disposed on the beam 80 at its front end and at right angles to the beam.

The other end of the cylinder and piston means 84 is pivoted on the cross pin 92 supported between the side walls of a housing 94 projecting rearwardly of the body from the main portion 96 of the blade 76. The lower end of the cylinder and piston means 84 is thus offset rearwardly of the body from the main portion 96 of the blade. This arrangement is of importance because it enables the means 84, when actuated hydraulically by known means, to draw the blade to the extreme front end of the body.

The blade comprises the main portion 96 which rests on the rear edge portion of a base channel member 98. Vertical strengthening ribs 100 extend up from member 98 in front of member 88 and are interfitted with and strengthened by a horizontally extending member 102 projecting forwardly, i.e. toward the front end of the body, from member 88.

The housing 94 is triangular, the side 95 of which, i.e. the top 95 of the housing 94, is inclined toward the rear of the body. An apron comprising portions 104 on either side of the housing inclines forwardly from the main portion 96 of the blade to the lower level portion 38 of the floor and each portion has a cutout 106 in its lower edge bridging the tongue or rail members 108 and 110 which project up from the floor portion 38 and are disposed in parallel directly above the bottom frame members 14 and 16 on which the floor portion 38 rests. The apron members are supported on the inclined rear faces of the pairs of vertical members 112 and 114 which are cut out on top to engage the base member 98 and extend down to the level of floor portion 38 on which they slide. The members 112 and 114 of each pair are spaced apart in close relation to the opposite sides of the members 108 and 110, and coact with said members to keep the blade normal to the sides of the body at all times, regardless of the strains tending at times to retard one end of the blade more than the other.

The apron also comprises portions 116 which are inclined forwardly from the main portion 96 of the blade to the top of the raised floor portions 40 and 42 respectively. The rearwardly inclined surface 95 of housing 94 and the apron portions 96 and 108 have different angles of inclination but they all have aligned lower edges which extend beyond the rear end of the body when the blade is moved to its rearmost position.

The cover 118 for the rear end of the body is hinged along its top edge by a series of two-part hinges 120, one leaf 122 of each of which is interfitted with and welded to the top cross member 36 at the rear end of the body frame, and projects rearwardly from and at right angles to member 36, and the other leaf 124 of which is attached to the top portion of the cover. The cover is dish shaped, curving outwardly from the rear end of the body to increase the capacity of the body when it is in closed position. The inner rim of the cover is faced with a sealing strip 126 which is disposed between the periphery of the rear end of the body and the rim of the cover when the cover is in closed position. Any suitable locking means may be provided for locking the cover in closed position. The cover may be raised and lowered by telescopic cylinder and piston means 128 of known kind, shown herein in FIG. 2 with one end pivoted on a cross pin 130 mounted within a bracket 132 depending from the rear end of beam 80 and the other end pivoted on the pin 134 supported in the bracket 136 on the inside of cover 118.

The structure disclosed herein provides a strong body which is economical and may be made of a size suitable for servicing private homes.

There has thus been provided a vehicle body in which the objects set forth above are accomplished in a thoroughly practical manner.

What I claim is:

1. A vehicle body comprising a frame having a bottom which comprises outer longitudinal channel members each comprising two parts spaced apart and interconnected by upwardly curving wheel covers defining wheel housings for the rear wheels of a chassis on which the body is mounted, two longitudinal channel members disposed in parallel between the outer members, and cross channel members, a two level sheet metal floor having a main portion resting on the bottom of the frame and lateral marginal portions offset upwardly from the main portion and extending over the wheel covers, vertical channel members extending upwardly from and similarly disposed along the outer members respectively of the bottom, channel members extending longitudinally between the vertical members on each side of the frame, and transverse channel members extending between the tops of opposed pairs of vertical members, sheet metal side walls fixed to the inside of the vertical members along each side of the frame, and sheet metal fixed to the under surface of the transverse members comprising the top of the frame, the sheet metal side walls being welded to the lateral margins of the sheet metal floor and top.

2. The body claimed in claim 1 including a beam extending longitudinally of the body and welded to top transverse members, the sheet metal between the beam and the top members being slotted and the weld union being through the slots.

3. The body claimed in claim 1 in which the sheet metal forming the top comprises strips extending transversely of the body and joined together along their lateral edges.

4. The body claimed in claim 1 in which the inner faces of the vertical frame members are offset outwardly ad-

jacent their upper ends and the sheet metal forming the top is bent down and secured between the outer surfaces of the sheet metal forming the body sides respectively and the inside surfaces of the offset portions of the vertical frame members.

5. The body claimed in claim 1 comprising means supported from the sides of said two longitudinal members of the bottom of the frame which are between the outer side members of the bottom, the said two longitudinal members being spaced apart a distance equal to the distance between the longitudinal members of a truck chassis to register with and be superimposed upon the said members of the truck chassis, and the said means comprising pairs of bolts and a cross member extending between, and threadedly engaged on, said pair of bolts, the bolts being long enough so that the cross member extends beneath the longitudinal chassis member.
